UNITED STATES PATENT OFFICE.

JOHN W. HEAPHY, OF ROCHESTER, NEW YORK.

TUMBLING-BARREL.

1,176,678.

Specification of Letters Patent. Patented Mar. 21, 1916.

Application filed September 2, 1914. Serial No. 859,770.

To all whom it may concern:

Be it known that I, JOHN W. HEAPHY, of Rochester, in the county of Monroe and State of New York, have invented certain new and useful Improvements in Tumbling-Barrels; and I do hereby declare the following to be a full, clear, and exact description of the same, reference being had to the accompanying drawings, forming a part of this specification, and to the reference numerals marked thereon.

My invention has for its object to provide a novel form of tumbling-barrel, such as may be employed for the purpose of polishing or cleaning or otherwise treating small articles by an agitating process, one of the purposes of the invention being to provide a construction that permits the more ready feeding or discharging of the articles to or from the machine.

20 A further object of the improvements is to afford an arrangement that will effect a quicker and more thorough agitation of the articles, the structure by which this result is accomplished being simple and economical to manufacture.

25 To these and other ends the invention consists in certain improvements and combinations of parts, all as will be hereinafter more 30 fully described, the novel features being 35 pointed out in the claims at the end of the specification.

In the drawings:

Figure 1 is a side elevation of an apparatus constructed in accordance with a preferred embodiment of the invention; Fig. 2 is a sectional view on the line 2^a—2^a of Fig. 1; Fig. 3 is a horizontal sectional view on the line 3^a—3^a of Fig. 1, and Fig. 4 is a 40 plan view of the tumbling cylinder with the brace rod and other parts removed.

Similar reference numerals throughout the several views indicate the same parts.

The invention is susceptible of various 45 applications, a more common use being in the polishing or abrading of small articles of metal or other material and in the present embodiment, which shows an instance of a member carrying out the invention, the 50 tumbler comprises a body A which is substantially cylindrical and is provided with the ends or heads B which extend beyond the periphery of the body and are connected by brace rods C. To the heads B are secured journals mounted in bearings, one of 55 said journals being provided with a fixed

pulley D which may be driven by either one of the oppositely moving belts E, the latter being controlled by shifters F.

The body of the tumbler is preferably formed of celluloid although it may be constructed of any other desirable material from a sheet that is bent upon itself circularly to the desired size of cylinder. The opposite ends of the sheet from which the tumbler is formed are attached together along the lines G and H, one end being extended to define a tapering portion which overlaps the under layer of the body as shown in Figs. 1 and 2. The overlapping portions are offset or embossed inwardly and outwardly as designated at I and J thereby affording a tapering opening K into which the articles can readily be fed and from which their discharge is easily effected. The articles are fed to the tumbler while it is in the position shown in Fig. 2, and are thereafter agitated and treated, by rotation of the cylinder in a clock-wise direction. To discharge the articles from the cylinder, its direction of movement is reversed so that as the opening K moves in an anti-clockwise direction, the contents are quickly removed, such removal being assisted by the tapering character of the discharging opening.

It is quite desirable that the article undergoing treatment be agitated to a maximum degree and to this end I may employ means for causing an additional movement 90 of the articles toward and from the ends of the cylinder and for dropping them from the top to the bottom of the cylinder at intervals. This may be accomplished by providing the body of the tumbler with a plurality of inwardly projecting baffles or ribs L which are preferably formed by embossing, and extend in curved lines from points between the center and ends of the cylinder to near the center of the cylinder, as shown 95 in Fig. 4. The result of this construction is that as the tumbler rotates, the curved baffles engage the articles and effect movement of the latter successively toward the center line of the cylinder. Certain of the 100 baffles L terminate at a point adjacent to a pocket or recess M formed by an outwardly projecting offset or embossed portion in the body of the cylinder. The articles when moved inwardly, away from the ends of the 105 cylinder by the baffles L, are caught up by the pocket M and carried upwardly by the 110

latter until it is nearly at the limit of its upward movement, whereupon they are dropped to the bottom and the operation is repeated.

5 The construction described affords a novel and extremely efficient arrangement for the purposes set forth, the tumbler being of simple and comparatively economical construction while at the same time, quite 10 strong, and rigid enough for the purposes intended, and it is to be understood that the present application is intended to cover any departures from the specific construction described that may come within the terms of 15 the appended claims.

I claim as my invention:

1. A tumbling barrel comprising a substantially cylindrical body formed from an integral sheet of material which embodies a 20 tapering overlapping portion, the part of the body underlying said overlapping portion being offset from the periphery so as to form a tapering charging and discharging opening.
- 25 2. A tumbling barrel comprising a substantially cylindrical body and a tapering overlapping portion which is offset from the periphery of the body so as to form a tapering charging and discharging opening.
- 30 3. A tumbling barrel comprising a substantially cylindrical body having a plurality of inwardly projecting baffles which extend in curved lines toward the center of

the body from points between the center and the ends of the body, the inner ends of 35 the baffles terminating adjacent to a recess or pocket formed by an outwardly extending offset portion on the body.

4. A tumbling barrel comprising a substantially cylindrical body and overlapping 40 portions which are offset in opposite directions from the periphery of the body affording a charging and discharging opening, the body being provided with a recess or pocket approximately opposite said charging and 45 discharging opening formed by an outwardly extending offset portion in the body, and a plurality of inwardly projecting baffles which extend in curved lines toward the center of the body from points between 50 the center and the ends of the body, the inner ends of the baffles terminating adjacent to said recess or pocket.

5. A tumbling barrel comprising a substantially cylindrical body embodying a tapering portion offset from the periphery of the body and overlapping a portion of the body which is offset in the opposite direction from the periphery of the body so as to form a tapering charging and discharging opening.

JOHN W. HEAPHY.
